UNITED STATES PATENT OFFICE.

FRANK ROBERT KRONFOTH, OF AMSTERDAM, NEW YORK.

RADIOANTENNA.

Application filed February 12, 1925. Serial No. 8,767.

To all whom it may concern:

Be it known that I, FRANK ROBERT KRONFOTH, a citizen of the United States, residing at Amsterdam, in the county of Montgomery and State of New York, have invented certain new and useful Improvements in a Radioantenna, of which the following is a specification.

The present invention relates to antennæ particularly designed for radio receiving sets and aims to provide a device which increases the capacity of the straight wire antennæ which are now commonly used on house tops and the like by radio broadcast fans in their receiving sets. The aerial is designed for use where the space for stretching the antenna wire is comparatively small.

The invention further aims to provide a device of this nature which will clarify the radio frequency waves so as to input the maximum energy into the antenna circuit of the receiving set.

A still further very important object of the invention is to provide a supporting structure in combination with an antenna which will compensate for the contraction and expansion of the antenna wire caused by the change in temperatures so that said wire will be maintained in a substantially taut condition at all times.

A still further object of the invention is to provide an antenna structure which is simple, efficient, strong, durable, inexpensive to manufacture, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is an elevation of the antennæ embodying the features of my invention, and

Figure 2 is a perspective view of one end thereof.

Referring to the drawing in detail it will

be seen that 1 and 2 represent posts or other like support having hooks 3 thereon. An insulator 4 is engaged with one hook and another insulator 5 is engaged on a cable 6 trained over a roller 7 supported in the frame 8 engaged with the hook 3 on post 1. This cable at its end may be fastened to the bottom of post 1 by any suitable means as at 9. A pair of steel discs 10 are provided with central openings for receiving eye bolts 11. Each disc 10 is provided with a series of apertures 12 which are arranged in pairs. In the present instance there are four pairs of these apertures 12 on each disc arranged at equal intervals thereabout adjacent the edge. Guy wires 13 are passed through the apertures 12. These guy wires are in the form of loops and are engaged with the insulators 4 and 5. The main antenna wire 14 is attached to the eye bolts 11 and the cable 6 is then pulled so as to cause the loop guys 13 and the main antenna wire 14 to become taut so as to take the position shown in Figure 1. When the cable 6 is pulled tightly the discs 10 will be flexed to some extent so that if the wire 14 expands these discs, because of their resilient nature will still maintain the wire taut, and if the wire contracts because of the heat, these discs 10 will flex further so as to take any excessive strain off the antenna wire.

From the above it will be seen that I have provided an antenna which will provide a greater capacitance than is possible with a single strand of wire and which this main antenna wire will be maintained in a relatively taut position at all times under ordinary circumstances. It will also be seen that the antenna of this nature will clarify the signal.

It is apparent that the present embodiment of the invention which I have described by way of example attains all the features of advantage enumerated as desirable in the statement of the invention and the above description and that numerous changes in the details of construction, and in the combination and arrangement of parts may be

resorted to without departing from the spirit or scope of the invention as hereinafter claimed.

Having thus described the invention, what

5 I claim is:—

In an antenna structure, a pair of discs, each disc provided with a central opening and a plurality of apertures adjacent its

periphery, eye bolts in the central openings, a wire having its ends attached to the eye **10** bolts, a pair of insulators, guy wires passing through the apertures of the discs and engaged with the insulators.

In testimony whereof I affix my signature.

FRANK ROBERT KRONFOTH.
